MARBLE REFACING MACHINE

Lowell Stetler, Orange, N. J.

Application September 30, 1935, Serial No. 42,943

3 Claims. (Cl. 51—180)

The invention relates to stone resurfacing machines and more especially to a marble resurfacing apparatus.

The primary object of the invention is the provision of a machine or apparatus of this character, wherein through the medium of a rotating element the surface of stone, marble or the like in place within a vertical wall or other structure can be operated upon for the resurfacing thereof and the polishing of the same, the machine or apparatus being readily portable so that it can be set up in confronting relation to the work to be acted upon thereby and the resurfacing element being readily adjustable or shiftable for an extended range of action upon the work and thus the necessity of hand resurfacing is eliminated with resultant dispatch in the handling of the work.

Another object of the invention is the provision of a machine or apparatus of this character, wherein the resurfacing element is self-adjusting to assure true operation upon the work for the resurfacing thereof and such element is motor driven and is susceptible of adjustment vertically and horizontally within determined limits.

A further object of the invention is the provision of a machine or apparatus of this character, which is comparatively simple in construction, thoroughly reliable and efficient in its operation, assuring a thorough resurfacing of the work confronted thereby automatic in action and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

40 In the accompanying drawings:

Figure 1 is a top plan view of a machine or apparatus constructed in accordance with the invention.

45 Figure 2 is a front elevation thereof.

Figure 3 is an end elevation.

Figure 4 is a fragmentary enlarged elevation partly in section of the movable carriage and adjuncts.

50 Figure 5 is a top plan view thereof.

Figure 6 is a fragmentary detail elevation of the electric solenoid control for the raising and lowering means for the machine or apparatus.

Figure 7 is a sectional view on the line 7—7 of Figure 6.

Figure 8 is a top plan view of the parts shown in Figure 7.

Figure 9 is a vertical sectional view through the resurfacing element of the machine or apparatus.

Figure 10 is a fragmentary sectional view on the line 10—10 of Figure 5.

Figure 11 is a fragmentary detail plan view showing diagrammatically the electric control mechanism of the machine or apparatus.

Figure 12 is an end elevation of a modification for the vertical adjustment of the runners of the machine or apparatus.

Figure 13 is a fragmentary top plan view of a still further modification.

Figure 14 is an end view thereof.

Figure 15 is a sectional view on the line 15—15 of Figure 13.

Figure 16 is a fragmentary sectional view through a further modified form of mounting for the resurfacing element.

Similar reference characters indicate corresponding parts throughout the several views in the drawings.

In Figures 1 to 11 of the drawings there is shown a machine or apparatus wherein the base 12 of the stand has equipped therewith spaced front and rear wheels 13 and 14, respectively, the axles for the latter wheels being carried in raising and lowering forks 15 swingingly connected with the base while the axles for the wheels 13 are fixed to the base and the purpose of the raising and lowering wheels 14 is to shift the same out of and into traction positions. When the wheels 14 are in traction position the same are held in that position by releasable latching pins 16 which are mounted in the base 12. When the wheels 14 are out of traction position the base 12 will be jacked by a rest block or beam 17 superimposed upon a foundation and beneath the base 12 so that the machine or apparatus will be stationary in confronting relation to work to be operated upon. Now when it is desired to transport the machine or apparatus the wheels 14 are lowered and by the travel of the wheels 13 and 14 upon the foundation the said machine or apparatus can be rolled from one locality to another.

Fixed to and rising from the base 12 is the vertical frame 18, it having at opposite ends the channeled tracks 19 for guide rollers 20 of runners 21 having forwardly projected horizontally disposed supporting arms 22 for a shiftable tracking board 23, it having at opposite ends thereof rack gears 24 meshing with racks 25 stationarily fitted with the arms 22 and these gears are common.

to a hand crank 86 so that the same can be turned for the shifting of the board 83.

Movable upon the board 83 is a carriage 87, it having traction rollers 88 movable in channeled 5 guide tracks 89 carried at opposite side edges of said board 83. Upon this carriage 87 are the spaced bearings 90 in which is journaled a hollow or tubular rotatable shaft 91 to which is yieldably coupled at 92 the resurfacing element 10 including the disk 93 carrying the sectors 94 of carborundum or other substance which are self-adjusting and disposed concentrically upon the disk 93 and are spring tensioned at 95, the self-adjusting of the sectors 94 permits the truing of 15 such sectors with relation to the work during the resurfacing thereof in the operation of the machine or apparatus.

Upon the bearings 90 is fitted an electric motor 96 which through the driving gear 97 meshing 20 with a ring gear 98 fixed upon the shaft 91 drives the latter. The shaft 91 has loose thereon the reversing beveled gears 99 and 100, respectively, these meshing with a driven gear 101 common thereto and fixed to a driven shaft 102 suitably 25 journaled upon the carriage 87 and having a worm screw 103 meshing with a worm gear 104 upon a stud shaft 105 having a rack gear 106.

This rack gear 106 meshes with a toothed rack 107 fixed longitudinally on the tracking board 30 83 and coextensive therewith for substantially its length. Splined or keyed to the shaft 91 is a friction clutch 108 which is located between the gears 99 and 100 and is alternately engageable therewith on the shifting of these gears 99 and 35 100 through the instrumentality of a shift bracket 109 slidably fitting a guide 110 on the carriage 87, the bracket 109 being provided with a clearance 111 for the shaft 102 which passes therethrough. The guide 110 carries a spring finger 40 112 for engaging the bracket 109 to frictionally hold the same in its shifted position. These gears 99 and 100 reversely drive the carriage 87 on the board 83 and the reversing operation of the gears 99 and 100 will be hereinafter fully 45 described.

At the top of the vertical frame 78 and suitably journaled in bearings 113 is a winding and unwinding shaft 114 which is common to windlasses 115, these being fixed to said shaft and on and 50 from which are wound and unwound raising and lowering cables 116 which are engaged at 117 with the runners 81 so that these will operate in unison for the raising and lowering of the arms 82. The shaft 114 has mounted at one end a hand crank 55 118 so that said shaft can be manually turned.

Fixed to the shaft 114 is a ratchet toothed latching disk 119, the teeth 120 being located at 60 opposite sides thereof and are arranged to allow a one-half revolution of the disk when released by coacting latches or dogs 121 pivoted at 122 in suitable bearings on a cross beam or bar 123 of the frame 78, these dogs or latches 121 being located at opposite sides of the disk 119 to cooperate with the teeth 120 for the latching of said 65 disk against turning movement in one direction while permitting the reverse turning of the disk so that the runners 81 can be elevated for adjustment to any desired height on the frame 78. When the runners 81 are elevated the teeth 120 70 on the disk 119 ratchet past the dogs or latches 121 while on the lowering of the runners it is necessary to alternately release the said dogs or latches 121 from the teeth 120 on the disk 119 as the dogs or latches are normally in the path 75 of these teeth and will latch the disk at each half

rotation thereof and in this manner on vertical adjustment of the runners 81 on the frame 78 the said runners can be held in vertically adjusted position.

Connected with the shift bracket 109 are reversely acting solenoids 124 included in independent normally open electric circuits 125 and 126, respectively, which are closed by switches 127, these being located on the carriage 87 at opposite ends thereof to be disposed in the path of actuating pins 128 selectively engageable at opposite sides of said carriage in holes 129 formed in the board 83 and arranged spaced from each other in a row longitudinally disposed of said board so that when the carriage 87 is traveling in one direction on the closing of a switch 127 the solenoid 124 in that circuit closed by the said switch will become energized for the shifting of the bracket 109 for the operation of the clutch 108 to reverse the direction of travel of the carriage 87. These pins 128 selectively engaging the holes 129 will control the extent of travel of the carriage 87 on the board 83 and in their cooperation with the switches 127 automatically effect the reversing of the travel of the said carriage 25 upon the board.

Connected with the dogs or latches 121 are reversely acting solenoids 130, these being included in the circuits 125 and 126 and alternately operate simultaneously with the alternate action of the solenoids 124 so that the said dogs or latches 121 will alternately release the latching disk 119 to permit automatic lowering intermittently of the runners 81 on the vertical frame 78 and in this fashion change the position of the resurfacing or polishing element including the cutting sectors 94 on the disk 93.

The frame 78 has therein the diagonal braces 131 and is rigidly supported by adjustable props 132 connected therewith and with the base 72. 40

Electric current is supplied to the circuits 125 and 126 by a power line 133 as is shown in Figure 17 of the drawings. The solenoids 124 when energized automatically shift the bracket 109 for the reverse drive of the carriage 87 on the board 45 83 while the solenoids 130 operate to alternately release the dogs or latches 121 from the disk 119 for the automatic lowering of the runners 81 simultaneously and in a step by step manner with the operation of the bracket 109 for reversing the direction of travel of said carriage.

The resurfacing element of the machine or apparatus can be brought into position with respect to the work when in a fixed position, as for example, when included in the vertical wall of a 55 building, so that the marble, stone or the like to be resurfaced can be operated upon by the machine or apparatus for that purpose. The working location of the resurfacing element of the machine or apparatus can be altered or changed 60 either automatically or manually and the cutting blocks or sectors of this element are self-adjusting in conformity with the surface acted upon thereby for resurfacing operation.

In Figure 12 of the drawings there is shown a 65 modification, wherein at the top of the frame of the machine there is arranged at each end at or close to the front of such frame a windlass 134 to which is connected a raising and lowering cable 135, it being trained over a guide pulley 70 136 which is located near the rear side or intermediate the front and rear of said frame and this cable from the pulley 136 is carried downwardly and attached at 137 to its companion supporting arm 82 for a shiftable tracking board 83. 75

The windlass 134 is carried by an operating shaft 138 suitably journaled at 139 at the top of the frame of the machine.

In Figures 13 and 14 of the drawings there is shown a further modification, wherein there is located between spaced parallel boards 140 at the top of the frame of the machine guide pulleys 141, these being journaled at 142 adjacent to opposite ends of said frame and have trained thereover raising and lowering cables 143 which are attached to and reversely wound and unwound from a windlass 144 common thereto. The windlass 144 is journaled at 145 midway of the longitudinal length of the frame of the machine and next to the front thereof. The axle 146 for the windlass 144 is operated by a hand crank 147 at the rear of the machine and this axle carries a ratchet pinion 148 with which cooperates a dog or pawl 149 pivoted at 150 at the top of the frame or machine. The cables 143 are attached to supporting arms 151 for the tracking board hereinbefore referred to. These arms 151 are upon runners 81 hereinbefore described.

In Figure 16 of the drawings there is shown a further modification of a resurfacing element mount, wherein the shaft 25 carries a disk 152 through which play in suitable openings near the periphery of the latter guide stems 153 fixed circularly to a backing plate 154 of a disk-like mount 155 for the resurfacing slabs or blocks (not shown). Interposed between the disk 152 and the plate 154 and centered with relation to the shaft 25 is a coiled cushioning spring 156 and in this manner the mount 155 is self-adjusting when the slabs or blocks are operating for resurfacing and polishing work. The stems 153 working in the disk 152 maintain these by nuts 157 of the mount 155 with the shaft 25 so that the latter will rotate said mount in the surfacing of the slabs or blocks.

What is claimed is:

1. A machine of the character described comprising a vertical frame having channeled tracks

at opposite ends, runners having guide rollers fitting said tracks, forwardly projecting arms on said runners, a shiftable tracking board carried by said arms, a carriage movable on said tracking board, rack and pinion connection between the board and said carriage, a motor carried by said carriage and operating said pinion, a surfacing element supported by the carriage and driven by said motor, and electrically operated means for reversing the travel of the carriage 10 on the tracking board.

2. A machine of the character described comprising a vertical frame having channeled tracks at opposite ends, runners having guide rollers fitting said tracks, forwardly projecting arms on 15 said runners, a shiftable tracking board carried by said arms, a carriage movable on said tracking board, rack and pinion connection between the board and said carriage, a motor carried by 20 said carriage and operating said pinion, a surfacing element supported by the carriage and driven by said motor, electrically operated means for reversing the travel of the carriage on the tracking board, and means for raising and lowering the runners in unison with each other.

3. A machine of the character described comprising a vertical frame having channeled tracks at opposite ends, runners having guide rollers fitting said tracks, forwardly projecting arms on 30 said runners, a shiftable tracking board carried by said arms, a carriage movable on said tracking board, rack and pinion connection between the board and said carriage, a motor carried by 35 said carriage and operating said pinion, a surfacing element supported by the carriage and driven by said motor, electrically operated means for reversing the travel of the carriage on the tracking board, means for raising and lowering the runners in unison with each other, and means 40 included with the said electric means and the last-named means for automatically effecting the lowering of the runners for changing the position of the surfacing element.

LOWELL STETLER.
